Application September 26, 1951, Serial No. 16,751

Term of patent 14 years

(Cl. D26—5)

To all whom it may concern:

Be it known that we, Anthony G. Horvath and William H. Kuner, residing at Dayton, Montgomery County, Ohio, and Robert L. Wolfe, residing at Springfield, Clark County, Ohio, all citizens of the United States, have invented a new, original, and ornamental Design for an Electric Motor, of which the following is a specification, reference being had to the accompanying drawing, forming a part thereof, in which:

Fig. 1 is a perspective view of an electric motor embodying our new design;

Fig. 2 is an end view thereof looking from the left of Figs. 1 and 3; and

Fig. 3 is a top plan view thereof.

We claim:

The ornamental design for an electric motor, substantially as shown.

ANTHONY G. HORVATH.
WILLIAM H. KUNER.
ROBERT L. WOLFE.
